IGNITION TIMING DEVICE FOR INTERNAL-COMBUSTION ENGINES, INCLUDING DISTRIBUTOR ROTATING AND LOCKING MEANS

Leroy Rider, Lake Charles, La., assignor of one-fourth to Oris Perron, Lake Charles, La.

Application November 4, 1948, Serial No. 58,167

3 Claims. (Cl. 123—146.5)

1

This invention relates to new and useful improvements in ignition timing devices for internal combustion engines and the primary object of the present invention is to provide a means whereby the driver of a vehicle can determine trouble in the ignition timing and spark plugs without any knowledge as to the mechanical functions of the engine.

Another important object of the present invention is to provide an ignition timing device for internal combustion engines including a means operated from a vehicle dash panel for rotating the distributor in either a clockwise or counter-clockwise direction, and embodying novel and improved means for locking the distributor in a selected rotated position to adjust the distributor timing.

A further object of the present invention is to provide an apparatus of the aforementioned character including novel and improved means for indicating the distributor timing, the flywheel timing and the distributor rotor contact.

A still further aim of the present invention is to provide a spark adjuster for vehicles that is quickly and readily applied to or removed from a vehicle in a convenient manner and which is simple and practical in construction, strong and reliable in use, small and compact in structure, efficient and durable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a diagrammatic view showing the present invention applied to a vehicle (shown in part);

Figure 2 is a fragmentary elevational view of a vehicle dashboard and showing the indicating means, locking means and distributor rotating means, used in conjunction with the present invention, applied thereto;

Figure 3 is a view showing the indicating means used in conjunction with the present invention, and with parts broken away for the convenience of explanation;

Figure 4 is a view showing the control switch used in conjunction with the present invention, and with parts broken away for the convenience of explanation;

Figure 5 is a fragmentary top plan view illustrating the means for rotating the distributor and

the means for locking the distributor in a locked position;

Figure 6 is a fragmentary elevational view showing the manner in which the flywheel timing means is supported relative to the flywheel; and

Figure 7 is a circuit diagram showing the manner in which the indicating lamps are operatively connected to the electrical circuit of a vehicle.

Referring now to the drawings in detail wherein for the purpose of illustration, there is disclosed a preferred embodiment of the present invention, the numeral 10 represents the power plant of a vehicle or an internal combustion engine generally, of any well known type, including a rotatable distributor 12 and a spark adjuster 14 that is secured to and movable with the distributor 12.

20 The method heretofore for retarding or advancing the ignition timing has been to loosen the distributor mounting screws and to rotate the distributor clockwise to advance or counter-clockwise to retard the timing.

25 It is the primary feature of this invention to provide a means operable from the dashboard 16 of the vehicle whereby the distributor may be rotated and locked in a selected adjusted position for controlling the ignition timing.

Distributor rotating means

30 Slidably received in a suitable aperture provided in the rear wall 18 of the vehicle motor housing 20, is a rod 22 that is also slidably received by an eye 24 fixed to the distributor 12. The opening in the eye 24 is sufficiently large to permit rotation of the distributor without the rod binding in the eye 24.

35 A stop 26 is fixed to the forward terminal of the rod 22 for a purpose which will later be more fully apparent.

40 Depending from an anchor bracket 28 detachably secured to the dash panel 16 and rear wall 18, is a ratchet 30 to which there is pivoted a hand operated lever 32 that is slidably and pivotally secured to the rear terminal of the rod 22.

45 A hand grip 34 is pivoted to the lever 32, and normally spaced from the lever by a spring 35, and a pawl 36 integrally formed with the hand grip 34 is adapted for engagement with the teeth 38 of the ratchet 30.

50 Pivoted at its center to the rod 22 adjacent the forward terminal thereof is a lever or rocking member 40 the lower end of which is secured to a flexible shaft 42 that is connected to the hand

grip 34. Guides 44 carried by the rod 22 slidably receive the shaft 42.

A ring or sleeve 44a slidably on the rod 22 is fixed to the forward end of a link 46 that is pivoted at its rear end to the upper end of the member 40.

Distributor locking mechanism

Secured to the spark adjuster or diaphragm housing 14, is an anchor plate 48 having an outwardly projecting portion or ratchet arm 50 that is formed with a slot 52.

A support bracket 54 mounted on the engine 10 and beneath the arm 50 is provided with an upstanding lug or pin 56 that is received in the slot 52.

The bracket 54 forms a support for a further bracket 58 to which there is pivoted a pawl 60 that is adapted to engage the spaced ratchet teeth 62 on the arm 50.

A coil spring 64, anchored at one end to the engine 10 and at its remaining end to the pawl 60, normally urges the pawl 60 into locking engagement between a selected pair of the teeth 62.

A sleeve 66 is detachably mounted on the dash panel or board 16 and slidably receives a cylinder 68 to which there is secured one end of an operating rod 70. The free end of the rod 70 is suitably secured to the pawl 60.

A lug 72 projects laterally from the cylinder 68 and is received in a slot 74 provided in the sleeve 66 when the pawl 60 is engaged between a selected pair of teeth 62.

In order to rotate and lock the distributor in a selected rotated position, the cylinder 68 is first pulled outwardly so that the lug 72 disengages the slot 74 and the pawl 60 disengages the teeth 62. The cylinder 68 is then rotated so that the lug 72 bears against one end of the cylinder to retain the pawl 60 in an unlocked position.

The hand grip 34 is pulled toward the lever 32 to disengage the pawl 36 from the ratchet teeth 38 and move the ring 44a against the eye 24. Next, the lever 32 and hand grip 34 are moved, together or individually to force the eye 24 and hence the distributor either clockwise or counter-clockwise a predetermined amount.

The lug 72 is then inserted in the slot 74 and the pawl 60 is re-engaged between a pair of the teeth 62 to lock the distributor in its adjusted position.

Indicating mechanism

The aforementioned distributor rotating means and distributor locking mechanism cooperates with an indicating means whereby the adjustment and necessary adjustment of the distributor is visible to the vehicle operator or serviceman. This indicating means includes a lamp housing 76 that is detachably secured behind the dashboard 16 by suitable fasteners 78.

A resilient pad or rubber wall 80 is clamped between the dashboard 16 and the housing 76 and includes a plurality of openings 82 that yieldingly receive lamp bulbs 84.

Sockets 86 are provided in the housing 76 for receiving the bases of the lamp bulbs 84 and a retainer plate 88 is removably secured to the housing 76 to retain the lamp bulbs positioned within the housing 76.

The dashboard 16 is provided with apertures 90 that register with the openings 82 provided in the wall 80 so that light rays emitted from the lamp bulbs will pass outwardly through the apertures 90.

The forward wall 92 of the flywheel housing 94 is provided with the usual opening 96 for observing the rotation of the flywheel 98 and mounted loosely within the opening 96 is a conductor 100 that is adjustably supported by a bracket 102 mounted on the wall 92. The reduced tip end 104 of the conductor 100 is positioned relative to a contact 106 on the flywheel 98 so that as the flywheel is rotated the contact 106 will come into a circuit closing position with the tip end 104.

The conductor 100 is connected to one of the lamp bulbs in the housing 76, for example lamp bulb 108, by conductor 110; the wire 111 between the coil 113 and the distributor rotor (not shown) is connected by conductor 112 to a further of the lamp bulbs, for example, lamp bulb 114; and the remaining lamp bulbs are connected by conductors 116 to the spark plugs 118.

20 The numeral 120 represents an insulated switch housing that is detachably mounted behind the dashboard 16 and which supports a plurality of fixed switch members 122, there being one switch member for each of the conductors 110, 112 and 116.

25 Slidably received in communicating openings 123 in the dashboard 16 and the switch housing 120, is a finger grip 124 that is detachably secured to an insulating block 126. The block 126 is provided with a plurality of bores 128 in which there are mounted sleeves 130 that slidably receive the fixed switch members 122.

30 Contacts or switch member 132 complementary to the members 122, are fixed in the sleeves 130 and are moved into circuit closing position with the members 122 as the block 126 is forced against the housing 120 by moving the hand grip 124 outwardly of the dashboard 16.

35 It will thus be seen that each of the conductors 40 110, 112 and 116 is provided with a switch controlling the current to the lamp bulbs, and by forcing the finger grip inwardly of the dash panel 16, the switches will be moved to a circuit open position and the lamp bulbs will not be energized.

45 Leading from or branching off of the carburetor fuel supply line 134, is a return conduit 136 that leads back to the fuel pump 138.

50 For use of the indicating means with vehicles wherein the timing mark is on the pulley 154, a timing pin 156 is used with a gap between the pin 156 and an adjustable conductor 158 on the engine block. The conductor 158 is connected to the indicating means as previously described.

55 It should be noted, that when the block 126 is raised toward the housing 120, in a circuit closing position, there will be a permanent gap or space between the switch members 122 and 132 for the timing lamp or lamp bulb 108. Further, if the distributor points are burned, or too close or too far apart, point light or lamp bulb 114 will not be energized nor will the other lamp bulbs.

60 When the distributor fires the number 1 spark plug for the engine, the current goes to the switch halves 120 and 126. The only time the current will jump the gap between the switch members 122 and 132 for the timing lamp 108 is when the pin on the fly wheel comes in line with the adjustable timing point.

65 70 Having described the invention, what is claimed as new is:

1. An ignition timing device for vehicle engines having a rotatable distributor and a spark adjuster movable with the distributor, said timing device comprising, a push rod, a guide car-

ried by said distributor slidably receiving the rod, a lever for moving the rod, a further lever pivoted at its central portion to the rod, a ring slidable on said rod, a stop on said rod, a link securing one end of said further lever to said ring, means for pivoting said further lever to force said ring against said guide, means for locking the guide clamped between said ring and said stop, and means applied to the spark adjuster for locking the distributor in a selected rotated position.

2. An ignition timing device for vehicle engines having a rotatable distributor and a spark adjuster movable with the distributor, said timing device comprising, a push rod, a guide carried by said distributor slidably receiving the rod, a lever for moving the rod, a further lever pivoted at its central portion of the rod, a ring slidable on said rod, a stop on said rod, a link securing one end of said further lever to said ring, means for pivoting said further lever to force said ring against said guide, means for locking the guide clamped between said ring and said stop, an arm fixed to said spark adjuster, means slidably supporting said arm, means connected to said arm for rotating said spark adjuster, and means engaging said arm for locking the spark adjuster in a selected rotated position.

3. An ignition timing device for vehicle engines having a rotatable distributor and a spark adjuster movable with the distributor, said tim-

ing device comprising, a push rod, a guide carried by said distributor slidably receiving the rod, a lever for moving the rod, a further lever pivoted at its central portion to the rod, a ring slidable on said rod, a stop on said rod, a link securing one end of said further lever to said ring, means for pivoting said further lever to force said ring against said guide, means for locking the guide clamped between said ring and said stop, an arm fixed to said spark adjuster, means slidably supporting said arm, means connected to said arm for rotating said spark adjuster, said arm having a plurality of spaced teeth, a pawl for locking engagement with the teeth, an operating rod for said pawl, and means normally urging said pawl into locking engagement with said teeth.
